UNITED STATES PATENT OFFICE.

GUSTAV BLUMBERG AND JOHN A. BUTKUS, OF BALTIMORE, MARYLAND.

ELECTRIC HORN.

1,317,123.

Specification of Letters Patent. Patented Sept. 23, 1919.

Application filed October 13, 1915, Serial No. 55,684. Renewed February 1, 1919. Serial No. 274,563.

To all whom it may concern:

Be it known that we, GUSTAV BLUMBERG and JOHN A. BUTKUS, citizens of the United States, residing at Baltimore, in the State of Maryland, have invented certain new and useful Improvements in Electric Horns; and we do hereby declare the following to be a full, clear, and exact description of the invention, such as will enable others skilled in the art to which it appertains to make and use the same.

Our invention relates to horns such as are used on automobiles, launches, etc.

The object of our invention is to produce a horn of this type which is sounded by an electric motor and in which means are provided for adjusting the relative locations of the sound producing mechanism and the electric motor, so that the quality of the tone emitted may be changed to suit the user, and so that wear can readily be compensated for.

In the drawings:—

Figure 1, is a perspective view of our improved horn showing the motor attached;

Fig. 2, is a plan view of our improved horn and motor. The horn is shown in section, one bearing of the motor is shown in section and part of one bearing support is broken away;

Fig. 3, is a view of the means by which the motor is attached to the horn looking in the direction of the arrow 3 in Fig. 2;

Fig. 4, is a view of the tappet attached to the diaphragm of the horn;

Fig. 5, is a perspective view of the ratchet wheel attached to the armature of the motor; and

Fig. 6, is a diagrammatic view of the connections between the battery, motor, and contact maker, and also of the mechanical connections by which the direction of motion of the armature is reversed.

In the drawings:—

10 is a bracket which may be attached by bolts passing through the holes 11 to any suitable part of an automobile, launch, etc. Secured to the bracket 10 by screws such as 12 is a casing formed of a flat portion 13 provided with a cylindrical flange 14, in the interior of which a ring such as 15 is secured by screws such as 16.

A diaphragm formed of a flat plate such as 17 provided with a cylindrical flange such as 18 rests against the ring 15, a reduced portion of said ring 15 being provided for the reception of the flange 18.

Another ring such as 19 provided with the chamfered portions such as 20—20 rests against the flat portion 17 of the diaphragm. A ring of paper or other suitable packing material such as 21 rests against the outer surface of the ring 19 and the flange 22 of the horn rests against the paper ring 21. Screws such as 23 secure the flange 22, paper ring 21, ring 19 and the flat portion 20 of the diaphragm to the ring 15.

Formed integrally with the flange 22 is the conical portion 24 of the horn which extends forwardly and terminates in the flat portion 25 provided with a central hole. A cone such as 26 has its small end projecting through the hole in the flat portion 25 and on the inside of said portion 25 the cone 26 is provided with a flange 27 which is soldered to the inner side of the flat portion 25.

Thus the flat portion 17 of the diaphragm, the conical portion 24 and the cone 26 together form a resonating chamber.

To the rear side of the flat portion 17 of the diaphragm, the tappet 28 is secured by rivets passing through the holes 29. The tappet 28 is formed with the rearward extension 30 provided with a surface 31 which forms a somewhat acute angle with the flat portion 17 of the diaphragm, and with another surface 32 joining the surface 31 which forms a less acute angle with the flat portion 17 of the diaphragm than does the surface 31.

A flanged ring such as 33 is soldered in a central hole provided in the flat portion 13 of the casing. Said ring 33 is provided with an interiorly threaded hole in which is screwed the threaded portion 34 of the ball bearing 35. A nut such as 36, provided with slots such as 37 for the reception of a spanner wrench, is screwed upon the threaded portion 34 of the ball bearing. The ball bearing 35 is provided with a raceway in which revolve balls such as 38 which serve to support and center the cone 39 attached to the shaft 40 of the motor 41.

The ball bearing 35 is provided with brackets, one of which is shown at 42, and the latter are secured to studs such as 43 which project from the field 44 of the motor.

A face ratchet wheel such as 45 is screwed upon the shaft 40 and a lock nut such as 46 prevents the loosening of the ratchet wheel 45 on the shaft 40.

The motor 41 is provided with an arma-

ture 46 having a commutator 47 against which bear brushes 48 and 49. The brushes 48 and 49 are each mounted in brush holders 50 and 51 and the latter are secured respectively to semi-circular plates 52 and 53. The plates 52 and 53 are insulated from each other and from the support 54 to which they are secured in any approved manner. The support 54 is revolvably mounted on a boss 10 not shown on bracket 55 and is retained in place thereon by the screws 56—56 which pass through slots 57—57 provided in the bracket 55. The bracket 55 is supported from the field magnet 44 by studs such as 74. 15 A stud 58 is secured in the bracket 55 and a brush mounted in a hole provided in the inner end of the stud 58 bears against one of the semi-circular plates 52 and 53. A similar stud 59 is also mounted on the 20 bracket 55, but insulated therefrom, and is also provided with a hole in its inner end in which is mounted a brush which likewise bears against one of the plates 52 and 53.

A lever such as 60 is formed integrally 25 with the support 54 upon which is mounted the semi-circular plates 52 and 53.

All parts of the motor being the subject of our application for U. S. Letters Patent Serial No. 55,685, filed October 13th, 1915, 30 will not be further described and will not be claimed in this application.

Referring to Fig. 6, the lever 60 is connected as by a link 61 with a lever 62. The lever 62 is fulcrumed as at 63 upon any approved part of the auto or launch and is retained in contact with the stop 64 by the spring 65. At the upper end of the lever 62 there is mounted a block of insulating material 66 upon the front of which is 40 mounted the contact plate 67. A lever such as 68 is fulcrumed as at 69 upon the main lever 62 and a spring 70 keeps the lever 68 in the position shown in Fig. 6.

The connections of our improved horn are 45 as follows:—

One side of the battery 71 is connected to the insulated stud 59. The other side of the battery 71 is connected to the contact plate 67. By reason of the fact that the stud 58 is 50 in electrical connection with the bracket 55 and that the brush end of the said stud 58 bears on one of the plates 52 or 53, while the brush in the insulated stud 59 also bears on one of said plates, it is evident that a 55 current of electricity will flow from the battery 71 to the stud 59 through the brush mounted in the stud 59, to the plate 53, to the brush 49, then to the commutator 47,

then through the brush 48 to the plate 52, through the plate 52 to the brush mounted 60 in the stud 58, and since said stud is in electrical connection with the bracket 55 and the latter is in electrical connection with the lever 60, the current will flow along the link 61 to the levers 62 and 68. 65

Hence, it is evident that if the lever 68 is pressed into contact with the plate 67 that the armature 46 will revolve.

The connections are so arranged that the motor will revolve in such a direction as to bring the surface 31 of the tappet 28 against the surfaces such as 72 of the ratchet wheel 45. This will give a tone of soft character, because the vibrations of the diaphragm will be less violent than when they are effected in a manner hereinafter described. 75

When a piercing tone is desired from the horn, the lever 68 is pushed against the contact 80 67 with sufficient force to bring the lever 62 away from the stop 64, and move the lever 60 sufficiently far around to bring the plate 53 under the stud 59, and the plate 52 under the stud 58.

This will reverse the direction of motion of the armature 46 and will bring the surface 32 against the surface 73 of the teeth of the ratchet wheel 45, thus producing a more violent vibration of the diaphragm and a piercing character of tone. 85

We claim:—

1. The combination with a diaphragm of a tappet thereon having two faces, an electric motor including a revolving shaft and brushes, a toothed wheel on said shaft, a source of electricity, a circuit closer for controlling the revolution of said wheel in one direction to strike one of said faces, and means for shifting the position of said brushes to reverse the direction of motion of said wheel to strike the other of said faces. 90 95 100

2. The combination with a diaphragm of a tappet, having two striking surfaces thereon, an electric motor including a revolving shaft and brushes, a toothed wheel on said shaft, a casing for said diaphragm, means 105 for supporting said motor on said casing, a source of electricity, a circuit closer and connections whereby said toothed wheel is caused to revolve to strike one of said surfaces, and means for reversing the direction 110 of revolution of said wheel to strike the other of said faces.

In testimony whereof, we affix our signatures.

GUSTAV BLUMBERG
JOHN A. BUTKUS.
